BASING CEMENT FOR LAMPS AND SIMILAR DEVICES

Noboru Yamashita, Kawasaki, Kanagawa-ken, Japan, assignor to General Electric Company, a corporation of New York

Application April 22, 1941, Serial No. 389,812
In Japan April 30, 1940

4 Claims. (Cl. 176—32)

My invention relates in general to electric lamps and similar devices of the type comprising a sealed glass envelope having operative elements and the like sealed therewith and a base affixed to a part of the envelope by means of a binding agent or basing cement. More particularly, my invention relates to an improved base construction for such devices.

The glass envelopes and bases of devices of the above-mentioned type are commonly attached to one another by a binder known as a basing cement. Heretofore, such cements were usually formed by mixing an inorganic filler with a binding agent, as for instance, powder of marble, alumina or magnesia and shellac solution. The binding operation is simple, but the bond between the glass envelope and base is not very strong. Consequently, the envelope and base may detach fairly easily when an external force is applied. In order to overcome such defect, it has been customary to impregnate the cement throughout with a synthetic resin such as Bakelite and then harden it under relatively high temperatures. Such a basing cement possesses very high binding power and provides an exceptionally strong bond between the glass envelope and the base.

In the manufacture and subsequent use of the above-mentioned devices, it has been found often necessary or desirable to remove the affixed base from the envelope, as for instance, when any inferior characteristic of the device is found by test or otherwise, or when the base is reclaimed as the life of the device terminates. In such cases, the base is removed by applying heat to that portion of the base which is cemented to the glass envelope, the heat carbonizing the basing cement and rendering the binding power thereof ineffective. However, in the case of the aforesaid synthetic resin-impregnated type of basing cement, the cement loses its binding power only after it is heated to an extremely high temperature. Consequently, the base is often injured or damaged by the intense heat. Even where the base is made of metal there is apt to be such damage from heat, and particularly so where the base is made of a compound, for instance, a synthetic resin such as "Bakelite."

One object of my invention is to provide a cement bond between the base and vitreous envelope of electric lamps and similar devices which will secure the base to the envelope with sufficient rigidity on the one hand while permitting relatively ready removal of the base without damage thereto on the other hand.

A feature of the invention is the use of a cement body which loses its binding power at relatively low temperatures and in which synthetic resin is impregnated only in a superficial layer in that surface of the cement body which contacts the vitreous envelope.

Further objects and advantages of my invention will be apparent from the following description and from the accompanying drawing in

10 which:

Fig. 1 is an elevation of a vacuum tube embodying the invention, part of the base being broken away to show the base and basing cement in section, and Fig. 2 is an enlarged cross-sectional view of a portion of the base and envelope and showing the cement bond construction according to the invention.

It is known that separation of lamp bases from the glass envelope is due primarily to the separation of the basing cement from that surface of the glass envelope in contact with the basing cement; and that the binding power of basing cement impregnated throughout with synthetic resin to the glass surface is far greater than that of a basing cement not so impregnated.

According to the invention, for that surface of the basing cement which is to contact the glass envelope a basing cement is used which has been impregnated with synthetic resin, thus utilizing the great binding power of such type basing cement, while for the surface of the basing cement in contact with the base and in the neighborhood thereof, a cement is used which loses its binding power at relatively low temperatures, i. e., one not so impregnated with synthetic resin.

To form such a composite basing cement construction, various processes may be employed, but it is preferable to form the same by applying a layer of ordinary basing cement (i. e., cement unimpregnated with synthetic resin) in a proper thickness on the inner surface of the base, next to coat a small amount of a solution of synthetic resin on either the inner surface of the layer of basing cement (i. e., that surface which is to contact the glass envelope) or on the surface of the glass envelope which is to be affixed to the layer of basing cement, then to assemble the base and glass envelope in proper interrelation, and finally to heat treat the assembled parts at the proper temperatures to harden or set the basing cement.

Referring to Fig. 1, the invention is there shown in connection with a vacuum tube comprising a sealed envelope 1 of glass or other

vitreous material having a neck portion 2 and containing one or more electrical energy translation elements (not shown) such as a filament or electrode. A base 3, of an insulating compound or of a metal, surrounds and is secured to the said neck portion 2 of the envelope by a layer of basing cement 4, formed in accordance with the invention. The basing cement 4 comprises an admixture of an inorganic filler with a suitable binding agent, as for instance, powder of marble, alumina or magnesia mixed with shellac solution. In accordance with the invention, the inner surface of the layer of basing cement 4, i. e., the surface immediately contiguous the glass envelope, is impregnated with synthetic resin to a proper depth as indicated at 5, i. e., to a depth sufficient to insure that the surface of the cement in contact with the surface of the glass envelope 1 is possessed of the greater binding power characteristic of a synthetic resin-impregnated cement. The remaining portion 6 of the basing cement 4 contiguous to the base 3, not being so impregnated with synthetic resin, accordingly will lose its binding power at relatively low temperatures. For the sake of clearness, the impregnated and unimpregnated portions 5 and 6 respectively of the basing cement are shown with a demarcation, but it will be understood that in the actual structure there is no such clear line of demarcation.

With such a basing cement construction, the bond between the glass surface of the envelope and the basing cement is sufficiently rigid to insure against rupture of the same by the normal shearing forces to which it is subjected during the handling and use of the device; while in case the base is to be removed, it is not necessary to heat the parts so intensely as to carbonize the hardened synthetic resin, inasmuch as the binding power of the unimpregnated portion 6 will soon be lost under relatively lower temperatures, thereby facilitating the removal of the base without causing any damage thereto.

What I claim as new and desire to secure by Letters Patent of the United States is:

1. An electrical device comprising a vitreous envelope having operative elements therein and a base affixed thereto by a layer of binding cement, the portion of said cement contiguous to said base consisting of a material which loses its binding power at a relatively low temperature and the portion of said cement contiguous to said vitreous envelope consisting of a material which loses its binding power only at a relatively high temperature and which possesses relatively great binding power.

2. An electrical device comprising a vitreous envelope having operative elements therein and a base affixed thereto by a layer of basing cement which loses its binding power at a relatively low temperature but which has its surface immediately contiguous said vitreous envelope impregnated with synthetic resin to thereby impart increased binding power to the said contiguous surface portion of said cement.

surface portion of said cement.

3. A bond for securing together a pair of members one of which is of vitreous material, said bond comprising a layer of basing cement between said members which loses its binding power at a relatively low temperature but which has its surface immediately contiguous said vitreous member impregnated with synthetic resin to thereby impart increased binding power to the said contiguous surface portion of said cement.

4. A bond for securing together a pair of mem-

4. A bond for securing together a pair of members, one of which is of vitreous material, which comprises a layer of basing cement between said members, said cement comprising a mixture of an inorganic filler and a binding agent which loses its binding power at a relatively low temperature, the surface of said cement immediately contiguous said vitreous member being impregnated to a limited depth with synthetic resin to thereby impart binding power to the said contiguous surface portion of said cement.
